(57) **CLAIM**

I claim the ornamental design for a CPAP device, as shown and described.

DESCRIPTION

FIG. 1 is a front perspective view of a continuous positive airway pressure (CPAP) device ("device").

FIG. 2 is a left side view of the device.

FIG. 3 is a right side view of the device.

FIG. 4 is a front view of the device.

FIG. 5 is a rear view of the device.

FIG. 6 is a top view of the device; and,

FIG. 7 is a bottom view of the device.

The broken lines shown in the drawings illustrate portions of the article and form no part of the claimed design.
